UNITED STATES PATENT OFFICE.

DANIEL O'HARA, OF WALTHAM, MASSACHUSETTS.

WATCH-CASE.

SPECIFICATION forming part of Letters Patent No. 309,354, dated December 16, 1884.

Application filed June 7, 1884. (No model.)

To all whom it may concern:

Be it known that I, DANIEL O'HARA, of Waltham, in the county of Middlesex and State of Massachusetts, have invented certain 5 new and useful Improvements in Watch-Cases, of which the following is a full, clear, and exact description.

This invention, in substance, consists, first, of a ring or band to contain the movement arranged therein in the usual or in any other suitable manner, and of a central shell or body or annulus closed on all its four sides and walls and surrounding by its inner wall the watch-movement, and provided at its back and front walls with risers, or otherwise suitably constructed for the attachment of a front bezel-ring, a back bezel-ring, a back cap or plate, and such other parts of the case as are or may be desired to complete it for the purpose intended.

It also, in substance, consists, second, of a ring or band to contain the movement arranged therein in the usual or in any other suitable manner, and of a central shell or body or annulus, either one or both, suitably constructed for the attachment of the other parts of the case as are or may be desired to complete it for the purpose intended, in combination with a bezel-ring constructed for the attachment of two crystals, one located inside of the other, leaving an inclosed air-space between.

It also, in substance, consists, third, of a ring or band to contain the movement arranged therein in the usual way or in any other suitable manner, and of a central shell or body or annulus, either one or both, suitably constructed for the attachment of the other parts of the case as are or may be desired to complete it for the purpose intended, in combination with a cap or plate constructed with double walls having an inclosed air-space between.

It also, in substance, consists, fourth, of a ring or band to contain the movement arranged therein in the usual or in any other suitable manner, and of a chambered central shell or body or annulus, either one or both, suitably constructed for the attachment of the other parts of the case as are or may be desired to complete it for the purposes intended, in combination with a winding-stem which passes through the pendant and the annulus

and movement-ring to the watch-movement within said ring, and is surrounded within 55 the chamber of the annulus by a wall thereof, which makes a bearing for said stem and closes the chamber of the shell to the entrance of dust and moisture thereto and to the movement.

The figures of the accompanying plate of drawings, forming a part of the specification, illustrate the present invention, and they are all in a similarly enlarged scale.

Figure 1 is in part a central transverse section and in part an edge view of a watch-case with the movement removed. Figs. 2 to 9, both inclusive, are sectional views at one side only of a watch-case, and they are all in illustration of the construction of the central shell 70 or annulus and movement ring or band in accordance with this invention, as heretofore stated; and Fig. 10 is a sectional view in detail through the pendant and winding-stem and a portion of the watch-case at such stem, 75 illustrating more particularly the fourth feature of this invention, as before stated.

In the drawings, A is the band or ring to contain the watch-movement. B is the central shell or annulus or body. C is the front bezel-ring, and D its crystal. E is the back bezel-ring, and F its crystal. G is the back cap or plate.

The movement band or ring A interiorly is adapted in any of the usual ways, or in any 85 other suitable way, for receiving and securing the watch-movement. (Not represented in the drawings.) This ring A exteriorly is surrounded by the central shell or body, B, preferably made with a recess or chamber, J; but 90 it may be made solid, or nearly so, using an inferior or baser metal—such as alabata, nickel, brass, or other metal or material—for the inner and unexposed portions thereof, and for its exposed sides or surfaces silver, gold, or 95 other precious metal or suitable material.

The annulus B and movement-ring A are either made of one piece of metal or of other suitable material, or of separate pieces of the same metal, or of different metals or materials, 100 secured together by solder or otherwise in any manner, and all so that the same together shall constitute one piece closed on all its four sides, and walls a, b, c, and d, surrounding by its inner side or wall the watch-movement, and at 105 its front and back sides or walls, a c, provided

with risers K L, or otherwise suitably constructed for the attachment of a front bezel-ring, C, and a back bezel-ring, E, a back cap or plate, G, and such other parts of the case 5 as may be desired to attach, to complete it for the purpose intended.

The one-piece annulus B and movement-ring A in Fig. 1 are shown as provided with risers interiorly screw-threaded for the attachment of a front bezel-ring, C, and a back cap or plate; in Figs. 2 and 8 as provided with an interiorly-screw-threaded riser for the attachment of the back cap or plate and an exteriorly-screw-threaded riser for the attachment of the front bezel-ring; in Figs. 3, 4, and 7 as provided with exteriorly-screw-threaded risers for the attachment of the front bezel-ring, C, and the back cap or plate, G; in Fig. 5 as provided with risers exteriorly screw-threaded for the attachment of the front bezel-ring, and interiorly screw-threaded for the attachment of the back cap or plate; and also the ring is exteriorly screw-threaded for the attachment of the back bezel-ring, E; and the construction shown in Fig. 6 differs from that of Fig. 5 in this respect, that the back bezel-ring is dispensed with and the back cap or plate, G, substituted therefor, thus dispensing with the riser for the back plate or cap.

30 In Fig. 9 the back cap or plate, G, is screwed over the outside of a riser at the back side of the annulus or ring B, and the front bezel is snapped upon the front side of the annulus, or attached thereto by a hinge.

35 Figs. 3 and 6 show the back cap or plate, G, as made of double walls M N, having a closed air-space, P, between, and Figs. 3 and 7 show the front bezel-ring, C, as made for receiving two separate crystals, D D², one inside of the 40 other, and having a closed air-space, Q, between.

45 In Fig. 10, R is the pendant-knob, and S is the pendant-ring, of the watch-case. T is a stem passing through the pendant-knob, annulus B, and movement-ring A to the watch-movement within said ring, which stem of itself and in its connection with the movement is a construction arranged for the winding of the watch-movement in any of the usual 50 ways.

55 U is a wall in the chamber J of the annulus, which surrounds the winding-stem T, and makes a bearing therefor, wholly closing said chamber about said stem, and thus stopping all communication for dust, moisture, and air to enter said chamber, and also assisting to still further prevent the possibility of air, dust, and moisture from passing to the movement along the tubular bearing between the 60 outside of the watch-case and the movement.

65 Leaving an air-space, J, in the back cap or plate, G, which may be also applied to a front cap or plate, and using two crystals, with an air-space between, together with a chambered annulus, separately and together tend to assist in reducing the liability of the movement be-

ing affected by heat or cold or magnetic or electric influences and forces or currents.

The attachment of the pendant ring S as heretofore made has been by hanging it at each 70 end in sockets or recesses at each side of the pendant knob, whereby, as well known, said ring is susceptible of being wrenched or drawn out of its said bearings with comparative ease by thieves. To obviate this said ring is provided with eyes or loops f, and these eyes suspended from eye-pieces g, attached to each side of the pendant knob R.

The pendant ring may be made in various forms and various ways—as, for instance, 80 either as particularly shown, or in the form of a cross-bar connected at each end by one or more links to the eyes of the knob, or in the form of a series of links in the form of a chain.

Having thus described my invention, what 85 I claim, and desire to secure by Letters Patent, is—

1. In a watch-case, a movement band or ring, A, and a central shell or annulus, B, made as one piece, and closed in the four sides a b c d, 90 and constructed for the attachment of other parts of the case, substantially as described, for the purpose specified.

2. In a watch-case, a movement band or ring, A, and a central shell or annulus, B, in combination with a bezel-ring constructed for the attachment of two crystals, having a closed air-space between them, substantially as described, for the purpose specified.

3. In a watch-case, a movement band or ring, 100 A, and a central shell or annulus, in combination with a cap-plate constructed with double walls and an inclosed air-space, P, substantially as described, for the purpose specified.

4. In a watch-case, a movement band or ring, 105 A, and a central shell or annulus, in combination with a bezel-ring constructed for the attachment of two crystals, leaving a closed air-space between, and with a cap or plate constructed with double walls and an inclosed 110 air-space, substantially as described, for the purpose specified.

5. In a watch-case, a movement band or ring, A, made as one piece, and a chambered central shell or annulus, B, closed on the four 115 sides a b c d, and suitably constructed for the attachment of the parts of the case, in combination with the pendant winding-stem T, and the wall or bearing U therefor of the shell, substantially as described, for the purpose 120 specified.

6. A watch-case having a pendant-ring, S, provided with eyes f, in combination with eyes g on the pendant, substantially as and for the purpose specified.

In testimony whereof I have hereunto set my hand in the presence of two subscribing witnesses.

DANIEL O'HARA.
